(57) **CLAIM**

The ornamental design for a portion of a rack for a storage container, as shown and described.

DESCRIPTION

FIG. 1 is a top perspective view of a portion of a rack for a storage container;

FIG. 2 is a front elevational view of the portion of a rack for a storage container of FIG. 1;

FIG. 3 is top plan view of the portion of a rack for a storage container of FIG. 1;

FIG. 4 is a bottom plan view of the portion of a rack for a storage container of FIG. 1;

FIG. 5 is a rear elevational view of the portion of a rack for a storage container of FIG. 1;

FIG. 6 is an elevational view of a first side of the portion of a rack for a storage container of FIG. 1; and,

FIG. 7 is an elevational view of a second side of the portion of a rack for a storage container of FIG. 1.

The broken lines depict environmental subject matter only and form no part of the claimed design.
